WILLIAM W. LOWERREE, OF ALBANY, NEW YORK.

Letters Patent No. 89,415, dated April 27, 1869.

IMPROVEMENT IN RUFFLING-ATTACHMENT FOR SEWING-MACHINES.

The Schedule referred to in these Letters Patent and making part of the same.

To all whom it may concern:

Be it known that I, WILLIAM W. LOWERREE, of Albany, in the county of Albany, and State of New York, have invented a certain new and useful Attachment to Sewing-Machines, called a "Ruffling-Gauge," and I do hereby declare that the following is a full, clear, and exact description thereof, which will enable others skilled in the art to make and use the same, reference being had to the accompanying drawings, forming a part of this specification, and to the letters of reference marked thereon, in which—

Figure 1 is a perspective view of my invention, as attached to a Florence sewing-machine.

Figure 2 is a front or longitudinal elevation.

Figure 3 is a view of the lever-end of my invention.

Figure 4 is a view of the outer end of the same.

Figure 5 is an end elevation, showing the relative positions of the principal parts of my invention, as also the position of the two pieces of muslin, or other goods or fabric, while being ruffled and sewed on.

Similar letters of reference indicate like parts in all the figures.

The principal object of my invention is to provide an attachment for sewing-machines, by means of which ruffling may be done with greater facility than at present, and in a manner always to be relied on.

This object I accomplish by constructing a suitable gauge, provided with tension-rollers and springs, and a separating-plate and lever, and ratchet and pawl, as will be hereinafter more fully described.

The back part of the gauge is made similar to the common and well-known gauges, used on sewing-machines generally, as shown at W in fig. 2, and is also fastened to the cloth-plate M, by means of thumbscrew h, in the usual and well-known manner.

The front part of the gauge is a suitable frame for carrying two small tension-rollers, A and B, side by side, as shown in figs. 1 and 5.

The first roller A has a screw-head on its outer end, for inserting a screw-driver, for the purpose of revolving the same, when entering the upper strip of cloth, which passes over roller A, then between rollers A and B, and under roller B, and separating and tension-plate H, as shown in fig. 5, in which K designates the upper, and L, the lower strip of cloth.

Tension-roller A carries a ratchet, D, of twenty-seven teeth, or of any other number of teeth desired. The above-named number I find sufficient for all ordinary purposes.

Said ratchet D is on the inner end of roller A, and on the outside of the roller-frame, as shown in fig. 2.

On the inside of the roller-frame, and on that end next the ratchet D, is a small toothed wheel, a, which meshes into a similar wheel on the same end of roller B, and which revolves said roller D.

The outer ends of rollers A and B are so hung in the roller-frame, as to admit a piece of cloth to be passed between them, from the end, as shown in figs. 1 and 4.

Roller A is pressed against roller B, by a flat spring, J, fastened, at its centre, in a stud, g, its two ends

pressing against side-caps on the ends of said roller A, as may be seen in figs. 1, 2, and 4.

Roller B may be suspended on screw-centres, as shown, on its outer end, in fig. 1.

H, in figs. 4 and 5, designates a metallic plate, fastened, at one end, to the lower part of the gauge, at its inner end, as shown in fig. 4.

Said plate H need not be more than one-half an inch wide, and of a length sufficient to reach nearly to the presser-foot of the machine.

w, in figs. 3 and 4, designates a stud, at the bottom of which is a wire, shown in fig. 4, by which pressure may be applied to the top of plate H, to increase the tension of the same upon the lower strip of cloth, so as to insure uniformity in the gathers taken up by the machine.

The front part of the gauge has a small space, S S, under it, to permit the lower cloth to pass freely.

C designates a bent lever, the lower end of which drives the roller A, by means of ratchet D and pawl E, in the well-known manner.

The upper end of said lever C is so adjusted, by means of set-screw f, as to be operated upon by the needle-bar P, when descending, as shown in fig. 1.

Lever O is carried upward by a bent wire spring, d, as shown in figs. 3 and 4.

It will be seen from the above description, that the length of the stitch will be regulated by the tension-rollers A and B, operated by means of lever C, and that the size of the gathers will depend upon the lower or regular machine-feed.

My improved gauge may be adjusted in its place, as shown in fig. 1, in a moment, and the lever O passes behind the presser-foot arm of the machine, the whole being secured to the cloth-plate M, by means of thumbscrew h.

A small guard-plate, b, may be secured over the driving or connecting gear-wheel on roller A, to prevent the upper strip of cloth from getting between the teeth.

It will readily be seen that, by means of this gauge, a certain and uniform feed of the upper strip of cloth, as well as of the lower one, will be given, thus insuring a regular and beautiful ruffling, and this without the aid of a skilful and experienced operator.

Having thus described my invention, and its mode of operation,

What I desire to secure by Letters Patent, is—

1. The tension-rollers A and B, and spring J, in combination with lever C and ratchet D, and pawl E, when combined and operated by the needle-bar of a sewing-machine, substantially as and for the purpose herein shown and described.

2. The separating-plate H, and tension-wire G, or their equivalents, in combination with rollers A and B, substantially as and for the purpose herein shown and described.

WILLIAM W. LOWERREE.
